R. KAMM

ABSORBENT SHIELD FOR GARMENTS

Filed July 5, 1922

UNITED STATES PATENT OFFICE.

RICHARD KAMM, OF CHICAGO, ILLINOIS.

ABSORBENT SHIELD FOR GARMENTS.

Application filed July 5, 1922. Serial No. 572,772.

To all whom it may concern:

Be it known that I, RICHARD KAMM, a citizen of the United States, residing at Chicago, in the county of Cook and State 5 of Illinois, have invented certain new and useful Improvements in Absorbent Shields for Garments; and I do hereby declare the following to be a full, clear, and exact description of the invention, such as will enable others skilled in the art to which it 10 appertains to make and use the same.

The primary object of this invention is the provision of a shield to be fitted to the armholes of garments, whereby to absorb 15 perspiration and afford protection and if needs be reinforce and give a finished appearance at the juncture of the arm with the body of the garment.

In accordance with the present invention, 20 the article comprises inner and outer elements of waterproof material, such as rubberized fabric, and an intermediate element of absorbent material, such as cloth, for taking up perspiration and thereby preventing 25 any uncomfortable feeling or any appreciable moistening of the garment.

Other objects and advantages will be apparent and suggest themselves as the nature 30 of the invention is understood.

While the drawings illustrate an embodiment of the invention it is to be understood that in adapting the same to meet different 35 conditions and requirements, various changes in the form, proportion and minor details of construction may be resorted to without departing from the nature of the invention.

Referring to the accompanying drawings forming a part of the application,

Figure 1 is a detail view showing the invention applied,

Figures 2 and 3 are obverse and reverse views, respectively, of the shield, and

Figure 4 is a transverse section on the line 45 4—4 of Figure 2, the parts being spread.

Corresponding and like parts are referred to in the following description and designated in the several views of the drawings by like reference characters.

The shield comprises essentially three parts, an outer part or flap 1, an inner part or flap 2 and an intermediate part 3. The several parts are of crescent outline and are secured adjacent the concave edge by means of a line of stitching 4. The outer part or flap 1 and the intermediate part 3 are preferably

of like size, whereas the inner part or flap 2 is somewhat smaller so as to expose a marginal portion of the intermediate part 3 adjacent the convex edge. The inner part 2 is secured to the intermediate part 3 adjacent its convex edge by a line of stitching 5. This prevents any wrinkling of the part 2 and results in a mutual bracing of the parts 2 and 3, whereby they are maintained in an 60 extended and smooth condition.

The parts 1 and 2 are of waterproof material, such as rubberized fabric, so as to resist penetration of moisture. The intermediate part 3 is of absorbent material, 70 such as cloth, so as to take up excessive perspiration and obviate any uncomfortable feeling and prevent concentration of moisture.

As indicated most clearly in Figure 1, 75 the shield when applied to a garment is arranged with the part 1 within the sleeve 6, and the parts 2 and 3 disposed to lie against the fore part 7 of the body of the garment, the part 2 being inside of the part 3 so as 80 to come between the latter and the person.

As shown in Fig. IV, the water-proof arm and body flaps 1 and 2 consist of separate pieces of sheet material with their upper edges secured by the stitching 4 to the upper 85 edge of the intermediate sheet 3, which is exposed between them, so that it may absorb moisture directly at this point.

The sheet-like part 3 combines ample capacity for absorbing moisture that might otherwise work around the part 2 and stain the garment, with relatively slight tendency to heat the wearer and cause perspiration. With this part 3 projecting beyond the lower edge of the part 2, perspiration running down the inner side of said part 2 will be caught and absorbed by its exposed margin. If profuse or prolonged, such perspiration will gradually work its way upward in this sheet-like part 3 by 90 capillarity, and thus be all the more readily evaporated by the circulation of air through the portion 7 of the garment. In this manner, the moisture will be continually dissipated without collecting in sufficient local 95 concentration to super-saturate the part 3 and stain the garment; while by the water-proof flap 2, the air will be kept completely away from the moist area of the body whence the perspiration proceeds. Attachment of the parts 2 and 3 to one another 100 substantially below their upper edges (by

the stitching 5, when employed) not only helps to prevent annoyance and discomfort from bulky wrinkling of the shield, but also makes it more effective in its functions 5 of protecting the dress from stain and the wearer from local chilling and catching cold.

What is claimed is:

1. A shield for the armseye of a garment, the same comprising an absorbent sheet part for insertion in the body of the garment, a waterproof flap for insertion in its sleeve, and a waterproof part inside only of said absorbent part, for insertion in the 10 body of the garment.
2. A shield for the armseye of a garment, the same comprising an absorbent sheet part for insertion in the body of the garment, a waterproof flap for insertion in its sleeve, 15 and a waterproof part inside only of said absorbent part, for insertion in the body of the garment, said absorbent part projecting beyond the lower edge of the last mentioned waterproof part.
3. A shield for the armseye of a garment, the same comprising an absorbent sheet part for insertion in the body of the garment, an outer waterproof flap for insertion in its sleeve, and a waterproof flap inside only of 20 said absorbent part, for insertion in the body of the garment; said absorbent part being secured to said flaps along its upper edge and projecting beyond the lower edge of the inner flap and being also attached to 25 said inner flap below its own upper edge.
4. A shield for the armseye of a garment,

the same consisting of separate inner and outer sheets of waterproof material as body and sleeve flaps, with an intermediate sheet of absorbent cloth for insertion in the body 40 of the garment outside of the inner flap, said sheets being secured together along their upper edges, and the intermediate one having its upper edge exposed, and also projecting beyond the lower edge of the inner 45 one.

5. A shield for the armseye of a garment, the same consisting of separate inner and outer sheets of waterproof material as body and sleeve flaps, with an intermediate absorbent sheet part for insertion in the body 50 of the garment outside of the inner flap, said sheets being secured together along their upper edges, and the intermediate one exposed along all its edges. 55

6. A shield for the armseye of a garment, the same consisting of separate sheets of waterproof material and an intermediate sheet of absorbent cloth, all secured together 60 along their upper edges by a line of stitching; said intermediate sheet being exposed along all its edges, with its lower margin projecting beyond the corresponding edge of one of the other sheets and secured thereto by a line of stitching. 65

In testimony whereof I affix my signature in presence of two witnesses.

RICHARD KAMM.
